UNITED STATES PATENT OFFICE.

ANDREW T. THAYER, OF NEW YORK, N. Y.

DESIGN FOR A BUCKLE.

Specification forming part of Design No. 5,403, dated December 5, 1871.

To all whom it may concern:

Be it known that I, ANDREW T. THAYER, of the city and State of New York, have invented or produced a Design for Buckles; and the following is declared to be a correct description thereof.

This buckle is especially intended for holding the straps of suspenders where they pass each other at the back; but the buckle may be used elsewhere.

In the drawing the design of the said buckle is illustrated.

The slots *a* and *b* are made in the sheet metal of the buckle, and the slot *a* is the longest. The

upper part of the buckle is wider than the lower, the top part having a projection in the middle, at *c*, between the curves *d d*; the corners at *e* are rounded, and the sides *f f* are curved inwardly. At the bottom is the downward central projection, at *g*, with inward curves at each side, at *i i*.

I claim as my invention—

The design for the sheet-metal buckle, substantially as described and represented.

Signed by me this 18th day of September, 1871.

ANDREW T. THAYER.
GEO. T. PINCKNEY.
CHAS. H. SMITH. (23)
